TIRE

Rush M. Johnson, Jr., Wadsworth, Ohio, assignor to The
B. F. Goodrich Company, New York, N.Y., a corpora-
tion of New York

Filed Sept. 1, 1960, Ser. No. 61,978

Term of patent 14 years

(Cl. D90—20)

FIG. 4

FIG. 5

FIG. 6

FIG. 1 is an elevational view of a tire showing my new design, it being understood that the full line portion of the design is repeated throughout the circumference of the tread of the tire;

FIG. 2 is an enlarged fragmentary perspective view thereof;

FIG. 3 is an enlarged fragmentary sectional view thereof taken substantially along line 3—3 of FIG. 1;

FIG. 4 is an elevational view of a modified form thereof;

FIG. 5 is an enlarged fragmentary perspective view of the modified form thereof; and

FIG. 6 is an enlarged fragmentary sectional view of the modified form thereof taken substantially along line 6—6 of FIG. 4.

The dominant features of my design reside in the full line portions of the drawings.

This application is a continuation-in-part of my co-pending application, Serial No. 55,266, filed March 31, 1959, now abandoned.

I claim:

The ornamental design for a tire, substantially as shown and described.
